UNITED STATES PATENT OFFICE.

THOMAS SAMUEL PARTIN, OF JUNCTION, ARIZONA.

FOOT-GUARD FOR RAILS.

1,068,161.

Specification of Letters Patent.

Patented July 22, 1913.

Application filed April 16, 1913. Serial No. 761,549.

To all whom it may concern:

Be it known that I, THOMAS SAMUEL PARTIN, a citizen of the United States, residing at Junction, in the county of Yavapai and 5 State of Arizona, have invented certain new and useful Improvements in Foot-Guards for Rails, of which the following is a specification, reference being had to the accompanying drawings.

10 This invention comprehends certain new and useful improvements in foot guards to be employed at railway switch points and the like.

An object of the invention is to provide 15 a foot guard of this character which will be of extremely simple construction and may be readily applied to fill the space between the main rail or switch rail and the guard rail, thereby making it practically impossible for a person's foot to become caught between said rails.

Another object is to provide a guard rail 20 of this character which may be formed of resilient sheet metal or other suitable material and will be of extremely simple construction and highly efficient in use.

With these and other objects in view, my 25 invention consists in certain novel features of construction, combination and arrangements of parts to be hereinafter more fully described, claimed and illustrated in the accompanying drawing, in which,

Figure 1 is a longitudinal section through 30 my invention in use, said view also showing the tie in section and one of the rails in elevation; Fig. 2 is a longitudinal section through the tie with the rails and guard plate in cross-section, a portion of the plate being shown in elevation; and Fig. 3 is a top 35 plan view of the rails and tie with my guard plate positioned between the rails.

Referring more specifically to the drawing, in which similar reference characters 40 designate corresponding parts throughout the several views, 1 designates the main or horizontal portion of my improved foot guard which has one end bent downwardly, as shown at 2 for engagement upon the base of the rails, it being understood that the 45 horizontal portion 1 rests above the tie and between the main rail 4 and the guard rail 5.

One longitudinal edge of the main or horizontal portion 1 of the plate is extended and bent upon itself for engagement over the guard rail 5, as shown at 6 and against the 55 opposite or outer face of the web portion of the guard rail as shown at 7, then extended downwardly over the base of the rail, as shown at 8 and provided with suitable notches 9 to accommodate the spikes 10 by 60 means of which the guard rail 5 is secured in position upon the tie 3. It will be understood that the portion 6 engaged over the top of the guard rail 5 conforms in shape to the 65 shape of the upper portion of the guard rail and the spikes 10 will serve to prevent longitudinal movement of the foot guard upon the guard rail 5 and will securely hold said foot guard in position with its main or horizontal portion 1 between the guard rail 70 5 and the main rail 4, thereby eliminating all danger of a person's foot becoming caught between the main rail and guard rail at this point.

It will be apparent that this foot guard 75 may be readily applied at switch points or other suitable points along the track and owing to the extremely simple construction of the guard formed of one piece of resilient sheet metal or other suitable material, the 80 foot guard will be extremely cheap to manufacture and when applied, will be highly efficient as well as durable in use.

While I have shown the preferred form 85 of my invention, it will be understood that if desired, minor changes in the details of construction may be made within the scope of the appended claim without departing from the spirit of my invention.

What I claim is:—

A foot guard comprising a horizontal portion, a downwardly directed portion connected with one edge of the horizontal portion, a turned portion connected with a second edge of the horizontal portion and 95 adapted for engagement over a rail while the horizontal and downwardly directed portions are adapted for engagement between said rail and a second rail spaced from the first rail, and a downwardly and 100 outwardly directed portion connecting with the turned portion and adapted for engage-

ment against the outer face and base of the first rail, said downwardly and outwardly directed portion being provided with notches for accommodating the spikes employed for securing the first rail upon its tie, whereby movement of the foot guard will be prevented.

In testimony whereof I hereunto affix my signature in the presence of two witnesses.

THOMAS SAMUEL PARTIN.
